MODULAR TERMINAL BLOCK

Raymond F. Piasecki, Hazlet, N.J., assignor to The
Thomas & Betts Co., Elizabeth, N.J., a corporation of
New Jersey

Filed Feb. 25, 1966, Ser. No. 1,195

Term of patent 14 years
(Cl. D26—1)

FIGURE 1 is a perspective view of a pair of complementary modular terminal block members in position for inter-connection, showing my new design;

FIGURE 2 is a top plan view of the complementary members in FIGURE 1 showing the same in connected relation;

FIGURE 3 is an end view in elevation of the connected members shown in FIGURE 2;

FIGURE 4 is a side view in elevation of the complementary member as seen to the left of the sheet in FIGURE 1; and

FIGURE 5 is a similar view of the other complementary member as seen to the right of the sheet in FIGURE 1.

I claim:

The ornamental design for a modular terminal block, as shown and described.
